UNITED STATES PATENT OFFICE.

ARTHUR P. ARMINGTON, OF WILLOUGHBY, AND WINFRED H. JUERGENS, OF CLEVELAND, OHIO, ASSIGNEES TO THE EUCLID CRANE AND HOIST COMPANY, OF EUCLID VILLAGE, OHIO, A CORPORATION OF OHIO.

WHEELED SCRAPER.

Application filed December 22, 1925. Serial No. 77,028.

This invention relates to wheeled scrapers intended to be trailed behind a means of motive power such as a gasoline tractor, and more particularly to a so-called rotary type of scraper wherein material to be moved is loaded into the scraper by a scooping motion of the load container or bucket, may then be transported after returning the bucket to its normal or carrying position, and ejected 10 when desired by a backward tilting of the bucket.

The objects of the invention are the production of a device capable of performing all of these operations as desired, light in 15 weight, simple in design and consequently inexpensive in construction, and capable of manipulation by the operator of the tractive means without interference with the attention required by the operation thereof; but 20 especially is it an object to provide means both manually and automatically adjustable, to compensate for variations in the quality and condition of the soil in which the scraper is to be operated.

The objects referred to are accomplished by a peculiar and novel manner of mounting the bucket in its frame, whereby the motion of the bucket while loading is automatically governed by the soil being loaded, the depth 30 of cut taken by the scraper varying dependent upon the resistance of the soil to the lip of the bucket against the forward motion of the scraper, the result being that the drawbar requirement of the scraper is automatically maintained within predetermined 35 limits, and an excessive maximum or "stalling" load upon the tractive means prevented. The arrangement which comprises our invention will be apparent from the following description with reference to the accompanying drawings in which:

Figs. 1 and 2 show a plan view and elevation respectively of the scraper in loading position.

Figs. 3 and 4 are sectional views along the line 3—4 of Fig. 1, but showing the bucket in dumping and carrying positions respectively.

Fig. 5 is a detail of an inclined plane and 50 its adjusting means employed.

Fig. 6 is a sectional detail of the hoisting drum appearing in Figs. 1 to 4, taken upon the line 6 of Fig. 1.

Fig. 7 is a sectional detail of the supporting means of the rear end of the bucket, 55 taken along the line 7—7 of Fig. 4.

The principal components of the scraper are the frame 1 supported on a pair of wheels 2, carrying a bucket 3 secured to the frame by the movable pivot 4 to be described in detail hereinafter; and the uprights 5 fixed upon the frame.

Supported by the uprights 5 is the shaft 6 which is caused to rotate as the scraper is advanced, by a chain 7 appearing in Figs. 65 1 and 2, running over sprockets mounted upon one end of the shaft 6 and the corresponding one of the wheels 2 respectively. Loosely mounted on the shaft 6 is a chain winding drum 8 provided on each side with 70 friction surfaces to engage corresponding friction surfaces on the members 9 between which the drum is mounted. One of the members 9 is secured to the shaft 6; the other one is keyed to rotate with the shaft but is 75 slidable longitudinally upon it to engage the drum 8 between the two members 9, by means of a helical cam which in turn may be rotated by the lever 11 to which is connected the control cable 12, and which is normally 80 spring retained in the position shown in Fig. 2. Thus when the lever is moved in a clockwise direction (Figs. 2, 3, 4) by the cable, the loose drum 8 is seized between the friction surfaces 9 and caused to rotate with the 85 shaft 6 so long as the tension on the cable is maintained.

Across the forward end of the bucket and projecting beyond the sides thereof is the rod 20 to the center of which is secured a bucket 90 chain the opposite end of which is secured in a deep, narrow groove in the drum 8; whereby by winding the bucket chain upon the drum the forward end of the bucket is raised and the bucket caused to tilt upon its axis 4, 95 the mechanical advantage of the winding drum being a maximum when the bucket is tilted farthest forward, and decreasing as the effective radius of the drum is increased by the chain being wound upon it as shown 100 in Fig. 6.

The forward end of the frame 1 carries the drawbar 13 by means of which the scraper may be attached to the draw bar of the tractive means.

At each side of the frame is mounted a

bearing in which is pivoted one end of a rod medially upon which is mounted the hand lever 14, and at each end a lever 16. Pivotally mounted upon each side of the frame 5 below the projecting ends of the rod 20, is a supporting member 18, connected by a link 17 with one of the levers 16. The links 17 are bent as shown in Fig. 1, to clear the ends of the rod 20, upon which are mounted rollers; and the members 18 extend somewhat rearward for a purpose to be described. The lever 14 and connecting linkage just described is normally maintained by gravity assisted by the spring 19 in the position shown in the figures, the upper ends of the supporting members 18 lying beneath the projecting ends of the rod 20 and thus preventing the bucket 3 from dropping below the carrying position shown in Fig. 4.

20 To each side of the frame of the scraper but spaced somewhat therefrom, and in the path of swing of the rollers upon the projecting ends of the rod 20, are secured inclined planes or ramps 22. These inclined planes serve to limit the downward travel of the forward end of the bucket, and the effective limit downwards is by reason of the incline dependent upon the longitudinal position of the bucket in the frame.

25 The bucket is pivoted at its rear upon a rod 4 extending across and somewhat beyond the sides of the bucket and supported at its ends in turn in the upper ends of link members 21, these links being pivotally secured at their lower ends to the bottom ends of the upright frame members 5. Adjustably positioned midway upon each of the uprights is a spring 23 connected at its lower end to a projection upon the upper portion 30 of the corresponding link 21, whereby the rear end of the bucket is resiliently urged upwards. The uprights 5 are formed of angle iron so that upward motion of the links 21 is limited to the position shown in

35 Figs. 3 and 4, and by means of a projecting finger at the bottom of each link, downward motion is limited to the position shown in Fig. 2.

40 Operation of the scraper is as follows: To load the bucket the lever 14 is raised, which shifts the position of the supporting members 18 and trips the forward end of the bucket, which drops downward, the rollers upon the projecting ends of the rod 20 now resting just above the inclined planes 22 instead of upon the supporting members 18, and the lip of the bucket resting upon the ground. As the scraper is advanced the lip digs into the earth as shown in Fig. 2, 45 which upon continued advance of the scraper is forced back into the bucket.

50 As the resistance of the earth to the entry therein of the lip of the bucket, and hence to the advancement of the scraper, approaches a predetermined limit dependent

upon the angle of the inclined planes 22 and the tension of the springs 23, the bucket is caused to make a scooping motion, the rear end of the bucket moving with respect to the frame backward and consequently downward upon an arc about the pivoted ends of the links 21, and the forward end of the bucket moving with respect to the frame backward and consequently upward, the rollers upon the rod 20 riding up the inclined planes 22. This compound scooping motion of the bucket with respect to the frame is opposed by the springs 23, and may be adjustably controlled by suitably locating the upper ends of the springs in the uprights 5, and adjusting the angle of the inclined planes 22.

Were it not for our provision of the means for accomplishing the bucket motion just described, the tendency of the lip of the bucket when lowered to the ground, would be to immediately dig into the earth at such a rapidly increasing angle therewith as to soon stall the scraper in earth of any very considerable firmness; further under such conditions it would be impossible to raise the bucket by power in the manner to be described. We have found that in practice the action of our bucket adjusts itself automatically to the conditions of soil encountered by the scraper and that thus with the employment of our device stalling of the scraper is almost entirely obviated, the bucket automatically tending to right itself upon meeting excessive obstruction by the soil, whether due to adverse quality or condition of the soil, or when the bucket has acquired a sufficient load thereof. In other words, as the scraper is advanced to load the bucket, the forward end of the bucket is by the arrangement described, automatically maintained at the proper elevation, dependent upon the resistance of the bucket to advance of the scraper.

When the bucket has become filled, to raise it to a position for transporting the load, the operating cable 12 is pulled, setting in motion the winding drum 8 connected by chain to the forward end of the bucket. As soon as the bucket is raised sufficiently for the ends of the rod 20 to clear the member 18 the spring 19 returns the linkage to the position of Figs. 1 to 4, and members 18 are thus brought into position to again support the bucket; therefore as soon as the bucket rises as far as the position shown in Fig. 4 the tension on the cable 12 may be released and the bucket will remain level. It will be noted that the angular relation of the parts is such that in the rearward or loaded position of the bucket in the frame, (the position of Fig. 2) the bucket chain has a greater mechanical advantage to elevate the bucket, than were the pivot 4 fixed upon the frame in the position of Fig. 4.

The load may thus be transported wherever desired.

When it is desired to dump the load, the operating cable 12 is again pulled, thus 5 further raising the bucket by means of the winding drum 8 to the position shown in Fig. 3 or sufficiently to slide the material back out of the bucket.

Upon release of the cable, the empty bucket 10 returns by gravity to the position in Fig. 4 where it remains until the scraper arrives at the loading point.

It is to be noted that manipulation of only 15 two controls—the lever 14 and cable 12—is required in the entire operation of our scraper. These controls are so located as to be within easy reach of the operator of the tractor pulling the scraper, the yoke 13 being so proportioned that when attached to 20 the drawbar of any standard tractor, the lever 14 is brought closely behind the operator's seat.

It is also to be noted that since all of the 25 operations of the bucket may be performed while the scraper is in locomotion, the functioning of the scraper may be accomplished as a continuous operation. The enormous 30 advantages of a grading unit capable of continuous performance by a single operator is obvious.

As appears in Fig. 1, the bucket is narrowest at its mouth, the sides extending back divergently so as to freely clear the material being handled, throughout the stages 35 of its passage through the scraper.

Attention is also called to the numerous provisions for adjustment of the scraper to various service conditions which are provided in the application of our invention 40 shown; the springs 23 are adjustably positioned at their upper ends upon the uprights 5; the spring 19 is adjustably positioned upon the yoke 13; the inclined planes 22 are adjustable angularly upon the frame 45 1 by means of extra bolt holes therein; tension upon the chain 7 is adjustable by an idler pulley as shown in Fig. 2.

While we have illustrated and described but a single example of scraper embodying 50 our invention, we do not wish to be limited more closely thereby than the scope of the spirit thereof. For example another type of friction clutch could be substituted for the one shown; the operating lever might 55 be shifted along the rod 15 to adapt the scraper to a particular tractor, or a pilot wheel or pair of wheels might be arranged to support the yoke 13 to adapt the scraper to be drawn by horses.

60 What we claim therefore, is:

1. In a scraper, a wheeled frame, a bucket mounted for movement therein, the rear end of said bucket being pivotally supported by 65 links in pivotal connection with said frame, means upon said frame operative to urge

said links to upstanding position, ramps secured upon said frame and adapted to engage members upon the forward end of said bucket to support the same, said links and said ramps being adapted for co-operation whereby generally rearward motion of said bucket in said frame during advance of said scraper effects a scooping motion of said bucket. 70

2. In a scraper, a wheeled frame, a bucket mounted for movement therein, said mounting comprising an oscillatory support adapted to allow arcuate bodily downward movement of the rear end of said bucket and pivotal upward movement of said bucket about 80 said rear end as said bucket is loaded, and means associated with said oscillatory support tending to maintain the rear end of said bucket in raised position. 85

3. In a scraper, a wheeled frame, a bucket mounted for movement therein, the rear end of said bucket being pivotally supported by 90 links in pivotal connection with said frame, means upon said frame operative to urge said links to upstanding position, ramps secured upon said frame and adapted to engage members upon the forward end of said bucket to support the same, said links and said ramps being adapted for co-operation whereby resistance of said bucket to advance of said scraper effects downward and rearward motion of the rear end of said bucket and upward and rearward motion of the forward end of said bucket with respect to said frame. 95

4. In a scraper, a wheeled frame, a bucket mounted for movement thereon, said mounting comprising an oscillatory support adapted to allow arcuate bodily movement of the rear end of said bucket and pivotal movement of said bucket about said rear end, means associated with said oscillatory support tending to raise the rear end of said bucket in said support, members upon said frame adapted to engage projecting members upon the forward end of said bucket to support the same and allow upward and rearward movement thereof whereby generally rearward motion of said bucket in said frame during advance of said scraper effects a scooping motion of said bucket. 105 110 115

5. In a scraper, a wheeled frame, a bucket mounted for movement therein, the rear end of said bucket being pivotally supported by links in pivotal connection with said frame, 120 means upon said frame operative to urge said links to upstanding position, ramps secured upon said frame and adapted to engage members upon the forward end of said bucket to support the same, said links and said ramps being adapted for co-operation whereby resistance of said bucket to advance of said scraper effects upward and rearward motion of the forward end of said bucket and downward and rearward mo- 125

130

tion of the rear end of said bucket with respect to said frame, said motion being in proportion to said resistance.

6. In a scraper, a wheeled frame, a bucket
5 mounted for movement therein, the rear end
of said bucket being pivotally supported by
links in pivotal connection with said frame,
means upon said frame operative to urge
said links to upstanding position, ramps se-
10 cured upon said frame and adapted to en-
gage members upon the forward end of said
bucket to support the same, said links and
said ramps being adapted for co-operation
whereby resistance of said bucket to advance-
15 ment of said scraper effects a scooping motion of
said bucket, said motion being in propor-
tion to said resistance, and manually con-
trolled means for elevating the forward end
of said bucket.

20 7. In a scraper, a wheeled frame, a bucket
mounted for movement therein, the rear end
of said bucket being pivotally supported by
links in pivotal connection with said frame,
means upon said frame operative to urge
25 said links to upstanding position, ramps se-
cured upon said frame and adapted to en-
gage members upon the forward end of said
bucket to support the same, said links and
said ramps being adapted for co-operation
30 whereby resistance of said bucket to advance
of said scraper effects upward and rearward
motion of the forward end of said bucket
and downward and rearward motion of the
rear end of said bucket with respect to said
35 frame, said motion being in proportion to
said resistance, and manually controlled
means actuatable by the wheels of said scraper
as the same advances for elevating the for-
ward end of said bucket.

40 8. In a scraper, a wheeled frame, a bucket mounted for movement therein, the rear end of said bucket being pivotally supported by links in pivotal connection with said frame, means upon said frame operative to urge
45 said links to upstanding position, ramps secured upon said frame and adapted to engage members upon the forward end of said bucket to support the same, said links and said ramps being adapted for co-operation whereby generally rearward motion of said bucket in said frame during advance of said scraper effects a scooping motion of said bucket, and displaceable members adapted to support the forward end of said bucket
50 clear of said ramps.

9. In a scraper, a wheeled frame, a bucket mounted for movement therein, the rear end of said bucket being pivotally supported by links in pivotal connection with said frame, 60 means upon said frame operative to urge said links to upstanding position, ramps secured upon said frame and adapted to engage members upon the forward end of said bucket to support the same, said links and 65 said ramps being adapted for co-operation

whereby generally rearward motion of said bucket in said frame during advance of said scraper effects a scooping motion of said bucket, and manually displaceable members adapted to support the forward end of said bucket clear of said ramps. 70

10. In a scraper, a wheeled frame, a bucket mounted for movement therein, the rear end of said bucket being pivotally supported by links in pivotal connection with said frame, 75 means upon said frame operative to urge said links to upstanding position, ramps secured upon said frame and adapted to engage members upon the forward end of said bucket to support the same, said links and 80 said ramps being adapted for co-operation whereby generally rearward motion of said bucket in said frame during advance of said scraper effects a scooping motion of said bucket, displaceable members adapted to 85 support the forward end of said bucket clear of said ramps and means to urge said members to bucket supporting position.

11. In a scraper, a wheeled frame, a bucket mounted for movement therein, the rear end of said bucket being pivotally supported by links in pivotal connection with said frame, means upon said frame operative to urge said links to upstanding position, ramps secured upon said frame and adapted to engage members upon the forward end of said bucket to support the same, said links and said ramps being adapted for co-operation whereby generally rearward motion of said bucket in said frame during advance of said scraper effects a scooping motion of said bucket and displaceable members adapted to support the forward end of said bucket clear of said ramps, said elevating means being adapted to raise the forward end of said bucket to a supported position upon said displaceable members, and operable to further raise said forward end to dump the contents of said bucket rearwardly.

12. In a scraper, a wheeled frame, a bucket having rearward connection therewith for relative longitudinal movement, means on said frame for supporting the forward end of said bucket in loading position and adapted to elevate said forward end dependent upon said longitudinal movement, whereby the depth of cut may be adjusted, means for yieldably opposing said movement, and means for tilting said bucket rearwardly about said connection to dumping position. 110 115 120

13. In a scraper, a wheeled frame, a bucket having rearward connection therewith for relative longitudinal motion, and for tilting movement to loading, carrying and dumping positions, means on said frame for supporting the forward end of said bucket in loading position and adapted to elevate said end dependent upon said longitudinal motion, means for yieldably oppos-

ing said motion, releasable latch means for supporting said bucket end in carrying position, and releasable means for elevating said bucket end whereby the bucket may be adjusted selectively to said positions.

14. In a scraper, a wheeled frame, a bucket having rearward connection therewith for relative longitudinal movement, said connection being adapted to lower the rear end of said bucket dependent on said longitudinal movement, means on said frame for supporting the forward end of said bucket in loading position and adapted to elevate said forward end dependent upon said longitudinal movement, whereby the depth of cut may be adjusted, and means for yieldably opposing said movement.

15. In a machine of the class described, a rigid frame, a scraper bucket in supported association therewith for movement thereon between digging and load-carrying and dumping positions, means for controlling said bucket movement to adjust the bucket to and from said positions, said frame including fixed axle means, wheels associated with said axle means to support said frame,

and cooperative parts on said frame and on said bucket arranged to be associated when said bucket is in digging position, for automatically controlling the elevation of the bucket lip dependent upon resistance of the bucket to advance.

16. In a machine of the class described, a wheeled frame, a bucket in supported association therewith for movement between digging and load-carrying and dumping positions, means for controlling said bucket movement to adjust the bucket to and from said positions, said association being adapted to allow bodily longitudinal movement of said bucket in said frame when in digging position, and including means for imparting to the lip portion of said bucket a vertical component of said longitudinal movement, whereby rearward bucket movement relative to said frame is accompanied by raising of the bucket lip, and means for yieldably opposing said rearward movement.

Signed by us, this 15th day of December, 1925.

ARTHUR P. ARMINGTON.
WINFRED H. JUERGENS.
